UNITED STATES PATENT OFFICE.

CHARLES H. CLARK, OF CRAFTON, PENNSYLVANIA.

LINING FOR BOX-CARS.

No. 918,965.

Specification of Letters Patent.

Patented April 20, 1909.

Application filed September 14, 1908. Serial No. 452,835.

To all whom it may concern:

Be it known that I, CHARLES H. CLARK, a resident of Crafton, in the county of Allegheny and State of Pennsylvania, have invented certain new and useful Improvements in Linings for Box-Cars, of which the following is a specification.

This invention relates to box car linings, and has particular reference to linings for metal cars, and the fixed or permanent linings hereinafter described are designed primarily for cars of that type, while the removable lining may be applied to cars constructed of either metal or wood, as much of the novelty resides in the mode of removably securing the lining without regard to the material of which the car is constructed even though as above indicated the improvements are especially adapted to metal cars.

20 A further object of this invention is to provide a car lining of such construction that any part thereof may be removed and replaced without disturbing other parts, the means employed for accomplishing this being of such simple construction that a broken or damaged part may be replaced by unskilled persons without sending the car to a shop for repairs.

30 The removable fastening means is preferably so constructed as to hold or clamp the lining boards in position by merely engaging their edges and not passing therethrough, so that the lining is ready for use as soon as it is cut to size. Means of improved construction is also provided for securing the lining at the vertical corners of the car.

40 In adapting the removable lining to a metal car, a further feature is the mode of utilizing the vertical stiffeners for spacing the lining inwardly from the side plates and for supporting the securing devices.

45 The invention also includes improved means for removably securing the ceiling, being designed with special reference to a roof having outside carlines, as shown in the Summers and Clark patent, No. 893,279, July 14, 1908.

50 With these and other objects in view, as will presently appear, the invention consists in the novel features of construction, and in the combination of parts, hereinafter fully described and claimed and illustrated by the accompanying drawings, wherein:

55 Figure 1 is an outline view in side elevation of a portion of a box car embodying the invention, and Fig. 2 is an end view of the

same. Fig. 3 is a fully developed section of the construction on line 3—3 of Fig. 1, and Figs. 4, 5 and 6 are similar views taken on lines 4—4, 5—5 and 6—6, respectively, of Fig. 2. Figs. 7 and 8 are detail views showing fixed or permanent linings designed especially for metal cars.

Referring to the drawings, 2 designates the girder-forming side plates, and 3 the bottom cord thereof. The roof sheets 4 are extended downward around and riveted to the outer legs of the inverted U-shaped top cords 5 of the side plates, the span or spread of the cord members corresponding to the full thickness of the lined side wall. Exterior carlines are provided for the roof in manner shown in the above mentioned patent, the edges of the plates being turned upwardly at 6, with the flanges of adjacent sheets embraced by the cord member 7 of inverted U-form, and with rivets passing through the latter and through the sheet flanges, as shown.

In the preferred adaptation of the invention the roof lining or ceiling boards 8 and the wall lining boards 8' are arranged in groups or sections corresponding to the space between the carlines and between the stiffeners, the ceiling securing means being coincident with the carlines and wall lining secures with the stiffeners. The boards are cut in lengths corresponding to the distance between adjacent carlines and between adjacent stiffeners, so that the board ends form the edges of the lining sections or groups which receive the detachable securing means. In using the term "boards" in the description and claims, I mean to include any and all forms of lining adapted for the purpose regardless of the material of which the same is formed, and regardless of size, length, width and arrangement thereof. In some cases corrugated sheet metal may be employed to advantage. Also, the side and ceiling linings may be formed of relatively thin or veneer boards, used in sheets of such size as may be most convenient.

For securing the ceiling, two bent up strip-like members 9 are fastened between and depend from flanges 6, said members 9 being bulged at 10 to form a socket between their lower or depending portions, and said members turned laterally at their lower edges, as indicated at 11, to form a backing for the lining boards. The socket-like hold-

ing and spacing element thus formed coöperates with a securing member which enters between the boards, said member being shaped from a strip of metal doubled upon 5 itself to form the central head-like part 12 which enters between the opposite bulges 10. The edges of the securing device are turned laterally in opposite directions, as indicated at 13, and are spaced from edges 10 11 of the fixed members a distance corresponding to the thickness of boards 8, thus confining the edges of adjacent rows of boards, as shown. The ceiling boards at the ends of 15 the car are held between the fixed angular members 14 and 14', as indicated at the right hand side of Fig. 4.

Boards 8 which line the side walls of the car are preferably arranged in vertical courses, fixed means being provided for detachably holding one end or edge of each 20 course and detachable holding means for the opposite end. As here shown, the boards of each course correspond in length to the space between adjacent vertical stiffeners 15 for 25 side plates 2, so that at each stiffener one course is held by fixed means and the adjacent course by removable means. Stiffeners 15 are each preferably of U form with a spread corresponding to the thickness of the 30 lined wall, and the inner angle thereof coöperates with angle 16 riveted to the stiffener to form a channel which receives one edge of the lining course. Secured to the back of the stiffener is the flexible strip-like member 35 17 which coöperates with the stiffener to form a socket. Edge 17' of member 17 forms a backing for the course of boards held by the detachable device, so that all the 40 courses line up as shown. The holding members which coöperate with the sockets consist each of a strip bent to provide a curved socket-entering inner portion 18 and an angular outer portion 19 which overlaps the boards, as shown. The formation is 45 such that with the course of boards in place, the detachable holding device may be entered in the socket where it is frictionally held and the boards secured.

When assembling the side lining, the 50 boards of each course are first inserted in the fixed holding means, and when the course is completed, the removable holder is sprung into place. Conversely, to take down the linings, the removable holding devices are 55 first taken out, after which the boards may be readily turned outward and withdrawn from the fixed device holding their opposite ends. The lower board of each course is preferably slipped behind an angle 20 riveted to the floor, thereby securely holding and protecting their lower edges.

At the vertical corners of the lining, the 60 two right angle courses of boards 8' are backed up by a pair of strip or plate members 21 which are riveted together and each

riveted between its edges to side plates 2. The edges of these members distant from the corner angle are bent inward at 22 to form backings for the boards. The inner portions of members 21 are bulged inwardly at 70 24 to form a socket, and this socket receives head 25 of the corner clamping member 26, the edges of the latter being disposed at right angles to each other and bearing against and holding one edge of each course, as 75 clearly shown in Fig. 5. When device 26 is in place, the extremities of the right angle courses are securely held, but upon being withdrawn from the socket the boards may be readily taken out. 80

In those forms of cars in which packed walls are desired, the space between the outer plates and the lining may be filled with saw dust or other suitable material, such fillings being indicated at 27. 85

While the lining above described is removably held and may be readily taken down, it is nevertheless quite as substantial and fully as serviceable as a lining built into a car and permanently fastened. 90

Of the numerous advantages of the removable lining, one is the ease and rapidity with which a car thus constructed may be lined, or an old lining removed and a new one inserted. It is also of particular advantage that repairs may be quickly and fully made by unskilled persons and without special tools, thus rendering it unnecessary to send a damaged car to a shop for that purpose. It is further characteristic of the 95 removable lining that the boards or other material may be cut to size in large quantities and kept at hand as required, thus greatly decreasing the cost and save material as compared with the special cutting of a 100 considerable quantity of lumber for each car lined as at present.

The fixed lining for metal or so-called steel cars may be constructed as shown in Figs. 7 and 8. In Fig. 7 the lining 30 is formed in 110 lengths or sections which fit between adjacent stiffeners 15 and is permanently held closely adjacent to the side plates 2 by angles 31 secured to the stiffeners. There may be a space 32 between the lining and the side 115 plates corresponding to the thickness of the laterally extending inner leg of the stiffeners, the leg spacing one edge of the lining from the outer plates, and a wire, rod or other spacing element 33 inserted back of the 120 lining adjacent the other stiffener. Thus all parts of the lining are held a uniform distance from the outer plates. In the adaptation of Fig. 8, a wood backing 34 is bolted to each of stiffeners 15, and the lining 30' is nailed thereto. In this arrangement, the lining may be in any desired lengths; and with the removable lining above described, the width or depth of the dead space behind the lining is determined by the width of the stiffeners. 125

I claim:

1. In a car lining, lining boards, and securing means detachably connected to the car and to the edges of the boards for removably securing the latter. 70
2. In a car lining, lining boards, holding means secured to the car, and board securing means detachably engaging the boards and held by the holding means. 75
- 10 3. In a car lining, lining boards, and board securing means inserted between the edges of adjacent boards.
4. In a car lining, lining boards, a yielding socket forming member secured to the car, and board holding means detachably held by the socket forming member. 80
- 15 5. In a car lining, lining boards, backing means for the boards, and detachable board securing means engaging the front faces of the boards and extending between the edges of adjacent boards. 85
- 20 6. In a car lining, lining boards, holding devices secured to the car and forming a backing for the boards, and a securing device entered between the edges of adjacent boards and held by the holding means, the securing device having laterally extended portions which overlap the front faces of the boards. 90
- 25 7. In a wall lining for cars, lining boards separated from each other to form vertical spaces for securing devices, elongated securing devices disposed vertically and entering between the boards and detachably engaging the latter, and means for holding the securing 95
- 30 devices to the wall of the car. 100
8. In a wall lining for cars, lining boards separated from each other to form spaces for securing means, and securing means entered in each of said spaces and connected to the 40 wall of the car, the securing means consisting of a fixed part with which the lining at one side is detachably engaged and a movable part which detachably engages the lining at the other side of the space. 105
- 45 9. In a wall lining for cars, side plates and vertical stiffeners therefor forming a backing for the lining, a lining bearing against the stiffeners, a fixed device coöperating with the stiffeners to form a channel-like holder 110 for one edge of the lining, and means for detachably holding another edge of the lining. 115
- 50 10. In a wall lining for cars, side plates, flanged stiffeners at the inner surface thereof, lining, an angle piece at each stiffener co-55 operating therewith to form a channel-like holder for an edge of the lining, and removable securing means detachably engaging the opposite edge of the lining. 120
- 55 11. In a wall lining for cars, side plates, flanged stiffeners at the inner sides thereof, a lining formed in sections, each stiffener forming a bearing surface for one edge of a lining section, a member secured to the stiffener and coöperating with the latter to form a 60 channel-like holder for the lining, a member 125
- fixed to form a backing for the edge of the next adjacent lining section, and a detachable securing device removably held by the last named member when engaging the edge of the next adjacent lining section. 70
12. In a wall lining for cars, a vertical corner construction consisting of upright means located at a corner and shaped to form a holding device, lining sections disposed angularly to each other, and securing means common to the angularly arranged sections and detachably held by the holding means. 75
13. In a wall lining for cars, a vertical corner construction consisting of means located at a corner between the lining and the outer surface of the car and formed with an inwardly facing socket, the angularly arranged lining sections, and securing means common to and entered between the sections and formed to be detachably held by the said 85 socket. 85
14. In a wall lining for cars, a vertical corner construction consisting of two upright members located at a corner between the inner and outer surfaces of the car wall and secured to the outer surface thereof, said members secured together and their adjoining edges shaped to form an inwardly facing socket, the outer edges of the members disposed in the planes of the respective lining sections, lining sections bearing against said edges, and securing means common to the sections and entered therebetween and formed with a head-like portion which is detachably held by the socket. 95
15. In a lining for cars, a socket forming member fixed to a car and having an edge which forms a lining backing, lining, and a fastening member having an edge embracing the outer face of the board, said member entered between the edges of adjacent boards and curved to be detachably held by the socket member. 105
16. In a car lining, the outer plates of a car, flanged stiffeners at the inner surface thereof and providing bearing surfaces for lining boards, a member secured to each stiffener and combining with the latter to form a channel for holding the edge of a lining board, a socket forming member secured to the stiffener and spaced from said angular strip member and forming a bearing for the inner surface of the next adjacent lining board, and a bent up strip-like member having an edge turned to embrace the outer surface of the last named lining board and curved to enter between the said socket-forming member and the stiffener and frictionally held thereby. 110
17. A top lining for cars consisting of lining boards, and removable holding means entered between the edges of adjacent boards for detachably securing the latter in place. 125
18. In a top lining for cars, lining boards, members fixed to the roof and depending 130

- therefrom and forming backings for the lining boards, and board securing means entered between the boards and detachably engaging said fixed members.
- 5 19. In a top lining for cars, two members depending from the roof and forming a holding socket between which a securing device enters, lining boards, and a board securing device detachably held in said socket.
- 10 20. In a top lining for cars, two oppositely bent holding members secured to and depending from the roof with their lower edges forming bearing surfaces for the lining boards and a space between said members forming a 15 socket, lining boards, and a holding device consisting of a strip of metal doubled upon itself with the edges thereof turned oppositely to embrace the outer surfaces of adjacent boards, the doubled portion of the device entered between the boards and detachably held by the socket forming members.
- 20 21. In a top lining for cars, members fixed in the corners of the car beneath the roof to form channels for lining boards, series of lining boards having the boards of the outer se- 25
- ries secured in said channels and with the edges of the boards of adjacent series spaced apart, and securing means entered through said spaces and detachably supported by the roof.
- 30 22. The combination of the side plates of a car, a top cord therefor consisting of an inverted U-shaped channel having its outer edge secured to the side plates, said channel having a span or spread corresponding to the thickness of the side wall and its lining, means secured to the inner edge of the cord for detachably holding the edges of the lining boards, means for removably holding the outer edges of the boards, and roof plates 35 having their outer edges bent downward over and secured to the outer portion of the cord-forming channel.
- 35 In testimony whereof I affix my signature in presence of two witnesses.
- CHARLES H. CLARK.
